United States Patent Office

Des. 194,888
Patented Mar. 26, 1963

194,888

JAR

John F. Dubbs, Lancaster, Pa., assignor to Armstrong
Cork Company, Lancaster, Pa., a corporation of Pennsylvania

Filed Apr. 9, 1962, Ser. No. 69,634

Term of patent 14 years

(Cl. D58—25)

The FIGURE is a side elevational view of a jar showing my new design.

The dominant features of my design reside in the portions shown in full lines.

I claim:

The ornamental design for a jar, substantially as shown and described.
